UNITED STATES PATENT OFFICE.

HERBERT A. WALLACE, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

CODE-SIGNALING APPARATUS.

Application filed March 12, 1925. Serial No. 14,941.

My invention relates to code signaling apparatus, and particularly to apparatus of the type comprising means for transmitting code combinations of alternating current, and a selector responsive to such code combinations.

Apparatus embodying my invention is particularly adapted for, though in no way limited to, use in railway traffic controlling systems.

I will describe one form of code signaling system embodying my invention, and will then point out the novel features thereof in claims.

In the accompanying drawings, Fig. 1 is a view, partly sectional, showing in front elevation, one form of selector embodying my invention. Fig. 2 is a view along line II-II of Fig. 1. Fig. 3 is a view, partly diagrammatic, showing one form of transmitting means for supplying energy to the selector illustrated in Figs. 1 and 2, and also embodying my invention.

Similar reference characters refer to similar parts in each of the three views.

Referring first to Figs. 1 and 3, the selector comprises an electromagnet A, a second electromagnet C, and a contact mechanism comprising a disk B controlled jointly by these two magnets. Magnet A comprises the usual two cores 3 of magnetizable material each provided with a winding 1 and connected at their upper ends by a back strap 2, also of magnetizable material. The armature 4 of magnet A controls a plunger 5 which passes through a hole in back strap 2. It will be seen that when magnet A is de-energized, plunger 5 drops to its lower position under the influence of gravity, but that when magnet A is energized armature 4 is attracted by cores 3 and the plunger 5 is moved upwardly.

Attached to back strap 2 is a U-shaped supporting yoke 9. In the upper arm 9a of this yoke is journaled in the hub 10a of a ratchet wheel 10 so supported as to allow free rotation about its axis and to also allow a small amount of motion parallel to the axis of the wheel.

The upper end of plunger 5 is provided with a bearing 6 to receive the lower end of a spindle 7, the upper end of which is journaled in wheel 10. Attached to spindle 7 is the contact disk B comprising a flat disk of

conducting material having a projection 17 outstanding from its edge for cooperating with certain fixed contacts 18, 19 and 20. The parts are so proportioned and disposed that when magnet A is de-energized to allow plunger 5 to assume its lower position, disk B is spaced from wheel 10 by a considerable distance but that when magnet A is energized, disk B is moved upwardly to engage the lower surface of wheel 10, lifting this wheel upwardly a small distance so that under this condition rotation of wheel 10 will also cause rotation of disk B by friction. The friction between disk B and wheel 10 may be increased by means of a washer 23 interposed therebetween.

Ratchet wheel 10 is controlled by magnet C, which magnet comprises two cores 12, each provided with a winding 15 and connected together at one end by a back strap 13. The magnet C further comprises a magnetized polarizing core 14 attached to back strap 13 and extending between cores 12. Pivottally attached to the free end of the core 14 is an armature 16 carrying a drive pawl 11 for engaging teeth 27 on the edge of wheel 10. When windings 15 of magnet C are supplied with current flowing in one direction armature 16 is swung to the left and when the direction of this current is reversed the armature is swung to the right. If, then, magnet C is supplied with alternating current, armature 16 is swung through one complete cycle of movement for each cycle of the alternating current. This motion of armature 16 actuates pawl 11 so that wheel 10 is advanced in a counter-clockwise direction as seen in Fig. 2, by one tooth for each half cycle of the alternating current supplied to magnet C.

A spring 8 having one end attached to the disk B and the other end attached to plunger 6, tends to move disk B in a clockwise direction as seen in Fig. 2, and the disk is therefore biased to the position in which it is illustrated in the drawing, further motion in a clockwise direction being prevented by engagement of projection 17 on the disk with a stop 26 on yoke 9. Under this condition contacts 17-18, 17-19, and 17-20 are all open.

If, however, magnet A is energized raising disk B into engagement with wheel 10,

and magnet C is supplied with alternating current to operate pawl 11, disk B is rotated against the bias exerted by spring 8 and after a certain number of alternations, projection 17 will be over, but not in engagement with contact 18. If magnet A should now become de-energized, armature A and plunger 5 will drop, allowing disk B to move downwardly. During this motion contact 17-18 will be momentarily closed. The disk B is then returned to its initial position by spring 8. Similarly, if magnet C is supplied with a certain greater number of alternations before magnet A is de-energized, contact 17-19 is closed for an instant as disk B drops, and if with a certain still greater number of alternations, the de-energization of magnet A allows contact 17-20 to become closed for an instant. In each of these cases it should be noticed that if the disk has not been moved to a position directly over one of the contact fingers 18, 19 or 20 when magnet A becomes de-energized, none of the contacts will be closed as the disk returns to its initial position.

The contacts on the selector may be used to control indicators or other apparatus in any desired manner. As here shown three slow acting relays 21, 22 and 23 are controlled by contacts 17-18, 17-19, and 17-20, respectively, so that each time one of such contacts is closed, the associated relay receives a surge of energy from a battery 24.

Referring now to Fig. 3, the reference characters 29 and 29^a designate the track rails of a stretch of track over which traffic normally moves in the direction of the arrow. The reference character Q designates, in general, a transmitter for supplying the rails with code combinations of alternating current. In the present form this transmitter comprises a plurality of contact disks 35, 36 and 37, of insulating material, rotated in unison by a constant speed motor M supplied with energy from a suitable source of alternating current such as an alternator G.

Contact disk 35 carries two oppositely disposed electrically connected contact segments 35^a of comparatively small peripheral length. Each of the remaining contact disks is similar to disk 35 except that the contact segments 36^a and 37^a are of successively greater peripheral lengths. Associated with each disk is a pair of fixed brushes 38 arranged to bear against the edge of the corresponding disk at diametrically opposite points thereon. The brushes 38 of each pair are therefore connected together intermittently as they engage the contact segments of the associated disk during rotation of the disks. Circuit controller 34, operated in any suitable manner, is arranged to connect alternator G across the rails 29 and 29^a through any selected one of the contact disks. When

this circuit controller 34 is open, no current is supplied to the rails of the stretch of track. When contact 34-34^c is closed alternator G is intermittently connected with the rails through disk 35 for comparatively short time intervals and the rails are supplied with code combinations of alternating current each made up of, for example, 15 alternations. When contact 34-34^b is closed the current supplied to the stretch is made up of longer code combinations as, for example, 25 alternations each, and when contact 34-34^a is closed, the track is supplied with still longer code combinations as of 35 alternations each. It should be noticed that in each case, each two successive code combinations are separated by an interval of time during which no current is supplied to the rails.

The selector is located on a train T, and is controlled in the following manner by the code combinations supplied to the trackway.

Carried upon the train T in advance of the forward axle 31 are two magnetizable cores 32 and 32^a, located in inductive relation with the two track rails 29 and 29^a, respectively. Core 32 is provided with a winding 33, and core 32^a is provided with a similar winding 33^a, these windings being so connected together, that voltages induced therein by alternating currents flowing in opposite directions in the two track rails at an instant are additive. The windings 33 and 33^a are connected, through suitable amplifying apparatus D with the windings 15 of magnet C on a selector similar to that shown in Figs. 1 and 2. Since amplifying apparatus usually delivers a pulsating direct current, a transformer Q is interposed between amplifying apparatus D and the windings 15 and these windings are therefore supplied with alternating current of the same characteristics as that existing in windings 33 and 33^a. The pulsating direct current delivered by amplifying apparatus D is supplied directly to windings 1 of magnet A of the selector.

Referring now to Figs. 1 and 2, as well as to Fig. 3, when contact selector, and the parts are in the normal or de-energized condition shown in the drawing, if contact 34-34^c is closed, the code combinations of 15 alternations each are supplied to the selector. The alternating current so supplied to magnet C operates pawl 11 to rotate wheel 10, and magnet A is also energized, so that disk B is lifted into frictional engagement with wheel 10 and therefore the disk is rotated by the wheel. Contact 18 is so located that when 15 alternations have been impressed upon magnet C, projection 17 is over contact 18. When relay A then becomes de-energized, disk B drops as explained hereinafter, and contact 17-18 is closed for an instant. Relay 21 then becomes energized.

During the time interval elapsing before the next combination of alternations, magnets A and C both remain de-energized, and disk B therefore returns to its initial position. The next code combination of alternating current will again close contact 17-18 as just explained. It will thus be clear that contact 17-18 is closed once for each code combination consisting of 15 alternations, but relay 21, being slow acting, bridges the time intervals between successive energizations and maintains its front contact closed as long as these code combinations are being received.

15 If contact 34-34^b of transmitter Q is closed the operation is similar to that already described except that since each code combination now comprises 25 alternations, disk B is rotated through a greater angle 20 for each combination and contact 17-19 is closed for an instant immediately at the end of each code combination so that relay 22 is energized. Relay 22 being slow acting, maintains its front contact closed as long as 25 these code combinations are received. Similarly if contact 34-34^a of transmitter Q is closed, contact 17-20 on the selector is closed once for each code combination and the front contacts of relay 23 are held in 30 the closed position. Relays 21, 22 and 23, may be used to control indicating or governing apparatus in any desired manner.

Should alternating current be continuously supplied to the trackway, disk B would 35 be rotated till projection 17 would be arrested by stop 26, and further motion of wheel 10 would simply be absorbed in friction. It should be noted that should this alternating current cease, none of the contacts would be closed, disk B dropping immediately upon the de-energization of magnet A, and returning to its initial position under the influence of spring 8.

One advantage of my invention is that the 45 transmitter comprises only simple apparatus of proven reliability and allows the use of alternating current with the attendant economy in transmission of power.

Although I have herein shown and described only one form of selector embodying my invention and only one form of apparatus for controlling such selector, it is understood that various changes and modifications may be made therein within the scope 55 of the appended claims without departing from the spirit and scope of my invention.

Having thus described my invention, what I claim is:

1. In combination, a stretch of railway 60 track, means for supplying alternating current to the rails of said stretch and for periodically interrupting such supply to provide code combinations made up of different numbers of alternations, a selector controlled 65 by said current in the track rails and re-

sponsive selectively to the number of alternations in said code combinations, and traffic governing means controlled by said selector.

2. In combination, a stretch of railway 70 track, means for supplying alternating current to the rails of said stretch and for periodically interrupting such supply after different numbers of alternations, a selector controlled by said current in the track rails 75 and responsive selectively to the number of alternations between interruptions, and traffic governing means controlled by said selector.

3. In combination, a stretch of railway 80 track, means for supplying alternating current to the rails of said stretch and for periodically interrupting such supply to provide code combinations made up of different numbers of alternations, a selector controlled by said track rail current and comprising a plurality of contacts one or another of which is momentarily closed after each combination depending on the number 85 of alternations in the combination, and traffic governing means controlled by said contacts.

4. In combination, a stretch of railway 90 track, means for supplying alternating current to the rails of said stretch and for periodically interrupting such supply to provide code combinations made up of different numbers of alternations, a selector controlled by said track rail current and comprising a plurality of contacts one or another of which is momentarily closed after each combination depending on the number of alternations in the combination, a plurality of slow 95 releasing relays one for each contact and each provided with an energizing circuit including the associated contact, the release period of each relay being greater than the interval between successive closings of its associated contact when the selector is receiving the combination to which such contact responds, and traffic governing means controlled by said relays.

5. In combination, a contact mechanism biased to an initial position, a first magnet, a second magnet, a source of code combinations of alternating current connected with said first magnet, amplifying apparatus and a transformer interposed between said source and said first magnet, means for connecting said source with said second magnet, and means controlled by said first magnet and effective when said second magnet is energized for moving said contact mechanism against such bias by an amount which depends upon the number of alternations in each said code combination.

6. In combination, a stretch of railway 100 track, means for supplying said stretch with code combinations of alternating current, a train carried selector responsive to the num- 105

ber of alternations in each such code combination, and governing means on the train controlled by said selector.

7. In combination, a stretch of railway track, means for supplying said stretch with code combinations of alternating current, a train carried selector, means on the train for supplying energy from the trackway to said selector, and governing means controlled by said selector in accordance with the number of alternations in each such code combination.

8. In combination, an operating magnet and a clutch magnet, means for supplying said magnets with alternating current interrupted to form code combinations made up of different numbers of alternations, a contact member biased to an initial position, a driving member, means interposed between said operating magnet and said driving member for moving said driving member a different amount during each code combination depending on the number of alternations in the combination, means operated by said clutch magnet when energized to operatively connect said contact member and said driving member, and a plurality of contacts one or another of which is closed momentarily upon release of said clutch magnet after each code combination depending on the amount of movement of the two members during such combination.

9. In combination, a first magnet and a second magnet, a source of code combinations of alternating current connected with said first magnet, amplifying apparatus and a transformer interposed between said source and said first magnet, means for connecting said source with said second magnet, a contact mechanism biased to an initial position, a driving device operated by said first magnet and effective when said second magnet is energized to move said contact mechanism away from such initial position by a predetermined amount for each half cycle of alternating current supplied to said first magnet, and indicating means responsive to the position of said contact mechanism.

10. In combination, a contact mechanism biased to an initial position, a first magnet, a second magnet, a source of code combinations of alternating current connected with said two magnets, and means controlled by said first magnet and effective when said second magnet is energized for moving said contact mechanism against such bias by an amount which depends upon the number of alternations in each said code combination.

11. In combination, a first magnet and a second magnet, a source of code combinations of alternating current connected with said two magnets, a contact mechanism biased to an initial position, a driving device operated by said first magnet and ef-

fective when said second magnet is energized to move said contact mechanism away from such initial position by a predetermined amount for each half cycle of alternating current supplied to said first magnet, and indicating means responsive to the position of said contact mechanism.

12. In combination, a stretch of railway track, means for supplying alternating current to the rails of said stretch and for periodically interrupting such supply to provide code combinations made up of different numbers of alternations, a train carried selector controlled by said current in the track rails and responsive selectively to the number of alternations in said code combinations, and governing means on the train controlled by said selector.

13. In combination, a stretch of railway track, means for supplying alternating current to the rails of said stretch and for periodically interrupting such supply after different numbers of alternations, a train carried selector controlled by said current in the track rails and responsive selectively to the number of alternations between interruptions, and governing means on the train controlled by said selector.

14. In combination, a stretch of railway track, means for supplying alternating current to the rails of said stretch and for periodically interrupting such supply to provide code combinations made up of different numbers of alternations, a train carried selector controlled by said track rail current and comprising a plurality of contacts one or another of which is momentarily closed after each combination depending on the number of alternations in the combination, and governing means on the train controlled by said contacts.

15. In combination, a stretch of railway track, means for supplying alternating current to the rails of said stretch and for periodically interrupting such supply to provide code combinations made up of different numbers of alternations, a train carried selector controlled by said track rail current and comprising a plurality of contacts one or another of which is momentarily closed after each combination depending on the number of alternations in the combination, a plurality of train carried slow releasing relays one for each contact and each provided with an energizing circuit including the associated contact, the release period of each relay being greater than the interval between successive closings of its associated contact when the selector is receiving the combination to which such contact responds, and governing means on the train controlled by said relays.

In testimony whereof I affix my signature.
HERBERT A. WALLACE.
